HYDRAULIC MOTOR FOR WAGON-DUMPS.

No. 909,279.

Specification of Letters Patent.

Patented Jan. 12, 1909.

Application filed January 8, 1906. Serial No. 295,194.

To all whom it may concern:

Be it known that I, JOSEPH E. CAMP, citizen of the United States, residing at Washington, in the county of Tazewell and State of Illinois, have invented certain new and useful Improvements in Hydraulic Motors for Wagon-Dumps; and I do hereby declare that the following is a full, clear, and exact description of the invention, which will enable others skilled in the art to which it appertains to make and use the same.

This invention has reference to wagon dumps of the hydraulic variety and has for its object the improvement and simplification of that class of mechanism.

A further object of the invention is to have a fluid pressure receiving cylinder which also answers as the fluid container or reservoir.

The invention further relates to certain other objects together with a peculiar combination of parts as will be pointed out in the following specification aided by the accompanying drawings in which,

Figure 1 is a side elevation of the wagon dump showing the pumping cylinder in part section. Fig. 2 is a plan view of the dump and, Fig. 3 is a detail view of a clutch device shown in Fig. 2.

A A indicate two parallel timbers of the dump-frame which are tied at their ends by means of short cross pieces B B as shown in Fig. 2, the latter resting upon the former and bolted thereto to constitute a rigid frame that may be dragged over the ground or otherwise transported from place to place, though from the structure to be described presently it will be seen that the mode of transportation can be more easily undertaken by placing the dump upon trucks or upon a wagon, this, however, being at the wish of the user.

I have not shown in the drawing the tongue by which the dump is transported from place to place since this has been brought out in my former application filed June 15, 1905, No. 265,301.

At the middle of the frame two cross members C C are secured to the longitudinal beams A A described, between which is located a vertically placed cylinder D having at substantially the middle of its length a horizontal pumping cylinder E. Diametrically opposite the pump is a boss F as shown in dotted lines in Fig. 2 and this boss

together with the pump E constitute trunnions for the cylinder D upon or by which it may rock as will be hereinafter explained, the cross members C C being bored to receive the said trunnions all of which will be understood without further explanation. The cylinder E is properly bored out to receive a piston E', being provided with a stuffing box at E', the piston-rod E³ having connected therewith an eccentric-rod G to which motion is imparted by an eccentric H on a transverse shaft J on one of the end members B such shaft receiving its motion from a horse-power or engine or other power. The eccentric is provided with a notched hub H' which is free of the shaft J and adjoining it is a shifting collar K keyed to the shaft by the feather L. This collar is grooved to receive a lever M pivoted on the dump frame by which it may be shifted toward or away from the eccentric whereby the said eccentric may be driven to operate the pump or released to stop the action of the latter.

Forward of the cylinder D is a small vessel D' for containing a small quantity of fluid and its top is connected into the upper part of the cylinder D by a pipe N, and at its side the vessel is again connected into the cylinder by a pipe O. The bottom of said vessel is connected to the pumping cylinder E by means of a pipe P which has a check-valve Q permitting fluid to pass from the vessel to the pump but not in the other direction. Connected into the pipe P between the check-valve and the pump is a pipe R which has connection with the bottom of the cylinder D. Said pipe R has a check-valve S therein for allowing the passage of fluid downward to the cylinder but not in the reverse direction. There is also connected into the vessel D' a pipe T having attachment with the pipe R between the check-valve S and its inlet end to the cylinder D. In this pipe T is a cut-off valve U operated by a lever V on a rock-shaft W journaled on the dump frame. The rock-shaft has a lever x extending up from said rock-shaft which is connected to the lever Y of the valve U by a link Z as shown in Fig. 1.

Within the cylinder D is a piston and piston-rod 2 and 3 respectively, the latter carrying at its upper end a cross-head 4, Fig. 1, having at each end a stirrup 5 adapted to rise beneath the front axle of a

wagon for holding and raising the same but this has been described in former applications of mine and will need no further explanation here. The stirrup mentioned is 5 provided with an additional stirrup 6, Fig. 1, one end of which is loosely connected to the stirrup 5 by means of a link 7. The stirrups 5 are used for wagons having a low axle while the stirrup 6 is employed for wagons 10 having higher axles and it will be seen that the latter stirrups can be thrown over out of the way as shown in dotted lines and may be replaced as shown in full lines at any time. A filling member 8 is formed with or secured 15 to the stirrup 6 of the desired height to accommodate the different axle positions as will be understood.

It will be noted that the frame A B is planked over so that the wheels of the wagon 20 may readily pass over or rest thereupon when dumping. Also, it is seen that approaches to the platform are provided so that the wheels can pass easily up and down. To the rear of the dump is stationed a chair 9 to 25 which is suitably secured the ends of two reaches 10 and 11, Fig. 2, the forward ends of which are secured to the platform as shown in said Fig. 2. Pivoted to the chair is a reach 12 which at its opposite end is 30 pivotally attached to the cross-head 4 by lugs 13 on the latter and a bolt 14. The length of the reaches 10 is such as to have the chair 9 just beneath the rear axle of the wagon. As the wagon rises the reach 12 35 steadies the piston-rod and tilts the cylinder D on its trunnions, this having been described in my former application.

In practice the cylinder D, the vessel D' and the pipes are all filled with the fluid, preferably oil of a heavy grade, and when it is desired to raise the piston 2 to dump a wagon, the clutch mechanism on the shaft J is thrown into engagement while said shaft is rotating thus setting the pump E to work. 40 Oil is thus drawn from the vessel D' and forced through the pipe R into the lower portion of the cylinder D beneath the piston thereof, the latter being raised. In rising, the piston displaces the oil lying above it 45 forcing said oil into the vessel D' through the pipes N and O from which it is drawn by the pump and forced into the bottom of the cylinder D. This action continues until the piston 2 has reached the dotted lines above 50 the pipe O as shown in Fig. 1 at which point the piston remains; the oil then merely circulates through and through the cylinder and the vessel D', the weight of the wagon being supported by the oil. If, however, the pump 55 be stopped at this time the piston will fall below the pipe O and remain fixed as before, still supporting the wagon. When desired to lower the wagon after the grain has been delivered, the valve U is opened and the oil 60 being under pressure within the cylinder 65

finds an outlet through the pipe R and pipe T back to the vessel D' from whence it flows back into the cylinder above the piston. The operator if he desires may interrupt the movement of the piston at any desired point 70 during the dumping operation by slightly opening the valve U thereby dividing the pressure from the pump so that a portion of the oil will return to the vessel D' while the residual pressure will be sufficient to sustain 75 the piston at practically a fixed position. The piston may be thus held at any height or it may be also controlled by means of the clutch mechanism described since all that is necessary is to stop the eccentric to allow the 80 entire apparatus to come to a position of rest, the piston being thus stopped at any height desired after which the valve U will permit said piston to lower as before.

I am not aware of a hydraulic jack of any 85 kind wherein a continuously operated pump furnishing a substantially uniform fluid pressure at all times has been employed and wherein said fluid pressure has been divided by a valve to permit a portion of the fluid to 90 return to the source from which it is drawn while at the same time using the remaining fluid to sustain the piston at a given point in the manner described herein.

By my improved construction it may be 95 seen that the cylinder constitutes its own reservoir for the bulk of the oil, the vessel D' and its connections being the means through which the oil passes from one side of the piston to the other. All of the oil necessary for 100 the full stroke of the piston cannot be held in the cylinder and the balance is held in the vessel D'. This will be clear when it is remembered that when the piston rod is entirely within the cylinder it occupies a certain place and must displace oil of an equal bulk which will be found in the said vessel D', there being already oil contained within and sufficient to fill the cylinder. As the oil is pumped from the top of the cylinder beneath the piston and the latter rises the piston-rod will be gradually replaced by oil. It is evident, therefore, that more oil is required 105 to fill the cylinder when the piston is up than when it is down. The needed amount for 110 the purpose is therefore drawn from the tank. It is clear from the foregoing that the piston could not be raised to its full height on account of lack of oil but by having an auxiliary oil container the lack is readily supplied 115 since after the pump has exhausted the oil from the top of the cylinder and forced it beneath the piston it then draws upon the oil in the vessel D'. The vessel also provides for the circulation of the oil through it from 120 the pipe T to the pipe P when the piston is held at any point below the outlet at O, (by the partially open valve U) the oil in that case neither entering nor leaving the cylinder at the top; the pump pressure, as before 125 130

stated, passing partly beneath the piston and partly to said vessel.

I claim—

1. A cylinder and its piston, a pump adapted for a continuous action a pipe connecting the same with the top of the cylinder, a check valve in said pipe, a second pipe connected at one end to the first between the check valve and the pump and connected at its other end into the bottom of the cylinder, a check valve therein, a third pipe connected into the second between its check valve and its end connected with the cylinder and having communication with the top of the cylinder, a manually controlled valve in said third pipe for permitting the free return of the fluid from the bottom to the top of the cylinder independent of the continuously acting pump, or for dividing the pressure above and below the piston to cause the latter to remain at a desired elevation, there being a second fluid connection for the pump the same having connection with the top of the cylinder for permitting suction from the latter to the pump, said connection also acting as a pressure relief for the pump when the piston has raised to and remains at a given position as described.

2. A cylinder and its piston, a pump adapted for a continuous action, there being two openings in the upper part of the cylinder, a single conduit connecting such openings with the pump, a check valve in said conduit, a conduit connected at one end to the first between the pump and the check valve and at its other end to the bottom of the cylinder, a check valve therein, a conduit connected into the last named pipe between its check valve and its end having connection with the cylinder, and having communication with the openings at the top of the cylinder, a controlling valve therein for governing the rate of flow of fluid therethrough from the bottom of the cylinder, or for dividing the flow under pressure substantially as and for the purposes described.

3. A substantially vertical cylinder mounted to oscillate on a horizontal axis, a piston therefor, a pump having the axis of its cylinder substantially coincident with the pivot of the cylinder and adapted for continuous operation, a pipe connecting the pump with the top of the cylinder, a check valve therein, a pipe connected at one end into said pipe between the check valve and the pump, and at its other end into the bottom of the cylinder, a check valve in said pipe, a pipe connected at one end to the last named pipe between its check valve and the cylinder, its other end having communication with the top of the cylinder, and a controlling valve in said pipe for the purposes explained.

4. In a hydraulic jack, a cylinder carried on horizontal trunnions, a pump adapted for continuous action whose cylinder axis is sub-

stantially coincident with the axis of the trunnions, a pipe connection between the pump and the top of the cylinder, a check valve therein, a second pipe connected into the first between the pump and the check valve and into the bottom of the cylinder, a check valve in said second pipe, a third pipe connected into the second between its check valve and the cylinder and having fluid connection with the top of the cylinder, and a controlling valve in said third pipe.

5. In a portable jack, a cylinder mounted on horizontal trunnions substantially midway between its ends, a continuously acting pump, one of the trunnions forming the cylinder for said pump, a fluid connection between the pump and the top of the cylinder, a check valve therein, a pipe connected into such fluid connection between the check valve and the pump and to the bottom of the cylinder, a check valve in such pipe, a pipe connected at one end into the latter and communicating with the top of the cylinder, and a controlling valve in said pipe.

6. A portable hydraulic jack comprising a substantially vertical fluid containing cylinder having transverse trunnions, and a piston and piston rod, a pump carried by the cylinder, a fluid conduit connecting the pump with the top of the cylinder at two different elevations, a check valve in the conduit, a pipe connected with the conduit between the check valve and pump, said pipe having connection with the bottom of the cylinder, a check valve in the pipe, a second pipe connected into the first between the check valve and the cylinder, its other end having connection with the conduit between the check valve and the top of the cylinder, a manually operated valve in the last described pipe, all of the described parts being carried by the cylinder, and a portable support upon which the entire apparatus is mounted.

7. A fluid containing cylinder and its piston, a pump, a vessel connected with the pump and connected also with the top of the cylinder said vessel being provided for holding fluid in excess of that contained in the cylinder, a check valve between the pump and vessel, a pipe connected between the pump and check valve and also connected into the bottom of the cylinder beneath the piston, a check valve in the pipe, a second pipe connected to the latter between its check valve and the cylinder and also connected into the vessel, and a controlling valve in the said second pipe for the purposes named.

8. A fluid containing cylinder, a pump, a vessel connected therewith and also having connection with the top of the cylinder, a check valve between the pump and the vessel, a pipe connected between the check valve and the pump and connected into the

bottom of the cylinder beneath the piston, a check valve in said pipe, a second pipe connected between the check valve and the bottom of the cylinder and connected also in the 5 vessel, and a controlling valve in said second pipe.

9. A fluid containing cylinder and its piston, a vessel for receiving and holding fluid expelled from the cylinder by the piston-rod,

10 a pump, a pipe connecting the pump and the bottom of the cylinder, a pipe connecting the fluid vessel and the pump, a relief pipe for the pump back to the fluid tank, pipe connections between the vessel and the top of the 15 cylinder substantially as described, there being provision for permitting flow of fluid from the vessel toward the pump through one of the pipes and from the pump to the vessel through another of said pipes, a control-

20 ling valve in the latter pipe, there also being provision for permitting flow of fluid from the pump to the bottom of the cylinder, the pipes connecting the vessel permitting flow of fluid in each direction to and from the cylinder and the vessel for the purposes set forth.

10. In a hydraulic jack, a substantially vertical cylinder, the piston and piston rod therefor, a support for the cylinder and on which said cylinder is adapted to tilt, and a member having pivotal connection with the 30 piston-rod and pivoted at its other end to the cylinder support for positively guiding the piston-rod in the arc of a circle in its vertical movements.

11. In a hydraulic jack, a fluid containing 35 cylinder, a piston and piston-rod therefor, a pump, a conduit connecting it with the top of the cylinder at two different elevations, a pipe connected into the conduit and also into the bottom of the cylinder, a check valve in the 40 conduit and a check valve in said pipe, and a manually controlled passage connected also with the conduit and with the pipe substantially as described.

In testimony whereof I affix my signature, 45 in presence of two witnesses.

JOSEPH E. CAMP.
